UNITED STATES PATENT OFFICE

151,874

DESIGN FOR A TIE CLASP

Charles W. Cole, Los Angeles, Calif.

Application September 23, 1946, Serial No. 133,513

Term of patent 14 years

(Cl. D17—10)

To all whom it may concern:

Be it known that I, Charles W. Cole, a citizen of the United States, residing at Los Angeles, in the county of Los Angeles and State of California, have invented a new, original, and ornamental Design for a Tie Clasp, of which the following is a specification, reference being had to the accompanying drawing, forming part thereof.

In the drawing:

Fig. 1 is an elevation of a tie clasp showing my new design;

Fig. 2 is a top plan view of the tie clasp shown in Figure 1; and

Fig. 3 is an obverse view of the tie clasp shown in Figure 1.

The essential features of my design reside in the specific type of the handle-like portion shown most clearly in Fig. 1.

I claim:

The ornamental design for a tie clasp, as shown and described.

CHARLES W. COLE.
